MASSAGE DEVICE

Harriette E. Niemicc, Miami, Fla.

Application July 26, 1939, Serial No. 286,676

1 Claim. (Cl. 128—300)

This invention relates to massage devices and more particularly to a suction cup especially designed for reducing or eliminating surplus fatty tissues from the body and for the treatment of 5 various physical ailments.

The object of the invention is to provide a massage device of simple and inexpensive construction by means of which the skin and muscles may be thoroughly kneaded or massaged so as to 10 induce the flow of blood to the treated area and eliminate excessive fatty tissues while at the same time stimulating and vitalizing the parts so that the flesh and muscles will be smooth and firm.

A further object of the invention is to provide 15 a manually operable massage device comprising a compressible bulb and a suction head connected therewith by an intermediate flexible neck or bellows whereby, when the bulb is compressed and manually reciprocated, said bulb will impart a pulsating movement to the flesh confined within 20 the area of the suction head to thoroughly massage the same.

A still further object of the invention is generally to improve this class of devices so as to increase their utility, durability and efficiency as 25 well as to reduce the cost of manufacture.

In the accompanying drawing forming a part 30 of this specification and in which similar numerals of reference indicate corresponding parts in all the figures of the drawing:

Figure 1 is a side elevation of a massage device embodying the present invention,

Figure 2 is a vertical sectional view,

Figure 3 is a side elevation showing the bulb 35 compressed and the massage device in position on the area of the flesh to be treated, and

Figure 4 is a vertical sectional view showing in full lines the position of the parts on the downward movement of the bulb and in dotted lines 40 the position of the parts on the upward movement of said bulb.

The improved massage device is principally designed for use by nurses, doctors and others for reducing or eliminating surplus fatty tissues from 45 the body and in the treatment of goiter and other physical ailments.

The device is preferably molded or otherwise 50 formed from rubber or other flexible material and comprises a compressible bulb 5 and a suction head 6 connected by a flexible intermediate bellows-shaped neck 7. The lower end of the bulb 5 communicates with the interior of the bellows 7 and the lower portion of the bellows communicates with the suction head 6 so that, when the bulb 5 is reciprocated, a pulsating movement will

be imparted to the flesh confined within the area of the head 6 thereby to induce the flow of blood to said confined area and thoroughly massage the parts. The suction head 6 is provided at its lower or open end with an inwardly extending flange 8 5 having a flat lower surface for contact with the body while the upper portion of the suction cup is tapered inwardly in the direction of the bellows-shaped neck 7 to form an inclined stop shoulder, as indicated at 9, defining a weakened 10 portion 10 at the junction of the wall 9 and the adjacent end of the bellows 7 so that, when downward pressure is exerted on the bulb, the lower inclined wall 11 of the bellows will become distorted and bear against the inclined wall or stop 15 shoulder 9 of the suction cup, as best shown in Figure 4 of the drawing. The fact that the upper portion of the cup is tapered also allows the bulb and the neck to have universal tilting movement to an inclined position in which the bulb may be 20 conveniently grasped when the cup is applied under an arm or to some other portion of the body which cannot be easily reached.

In using the device, the surface of the body to be treated is first preferably moistened with water 25 or an Epsom salt solution, after which the bulb 5 is compressed and the suction head 6 pressed against the part to be treated and in which position the suction within the head 6 will prevent displacement of the device. The operator then grasps the bulb 5 and rapidly reciprocates the same so as to impart a series of pulsations to the flesh confined within the area 30 of the suction head which vibrations or pulsations tend to eliminate or reduce all surplus fatty tissues and render the flesh and muscles smooth and firm. On the downward movement of the bulb 5, the lower inclined wall 11 of the bellows-shaped neck 7 will be distorted and bear against the inclined wall or shoulder 9 so as to limit 35 the downward movement of the bellows and prevent said bellows from coming in contact with the flesh at the suction head, as indicated in full lines in Figure 4 of the drawing, and on the upward movement of the bulb, the inherent elastic properties of the bellows 7 will cause it to assume 40 its normal shape, as indicated in dotted lines in said figure. It will therefore be seen that compression of the bulb 5 serves to produce sufficient 45 suction to hold the device on the flesh and after being so positioned manual reciprocation of the bulb causes rapid deformation and restoration of the lower inclined wall 11 of the bellows 7, thereby effecting corresponding pulsations of the body 50 55

tissues confined within the suction head without any mechanical parts of the device other than the suction head coming in contact with the flesh. It will further be noted that, when the bellows 7 is in collapsed position, the weakened or restricted portion 10 permits the bulb 5 together with the bellows to be tilted freely in a circular path on the inclined wall 9 of the suction head as a universal joint to selected inclined positions so that pulsations 10 may be imparted to the entire area of the flesh confined within the head.

While the device is principally designed for removing surplus fatty body tissues, said device may be used with equally good results in the treatment 15 of various physical ailments, such as goiter, swellings, pains and the like, as the pulsations produced by reciprocation of the bulb induces the flow of blood to the affected parts and thus promotes a healthy condition of the body tissues and 20 tends to reduce swelling and the like. When the device is to be removed, sufficient pulling force is exerted to detach it.

It will, of course, be understood that the massage devices may be made in different sizes and shapes without departing from the spirit of the invention, the salient feature of which resides in the bellows-shaped neck which causes rapid pulsations of the flesh within the suction head when the compression bulb is reciprocated. 5

Having thus described the invention, what is 10 claimed as new is:

A massage device comprising a compressible bulb, an open-ended suction head having its upper portion tapered to form an upwardly inclined stop shoulder, and a reversely inclined collapsible bellows connecting the bulb and shoulder, said 15 bellows when collapsed engaging the shoulder to limit the downward movement of the bellows and prevent contact thereof with the flesh at said suction head. 10
